[57] CLAIM

The ornamental design for a hat having a nappy surface, as shown and described.

DESCRIPTION

FIG. 1 is a front perspective view of a hat having a nappy surface showing our new design;
FIG. 2 is a front view thereof;
FIG. 3 is a rear view thereof;
FIG. 4 is a side view thereof with the other side being symmetrical thereto;
FIG. 5 is a top view thereof;
FIG. 6 is a front elevational view of a hat having a nappy surface showing our new design, the only difference being the front crown logo; and,
FIG. 7 is a front elevational view of a hat having a nappy surface showing our new design, the only difference being the front crown logo.

The bottom view of the hat is omitted because the bottom of the hat is plain and unornamented. Also, the rear, side, and top views of the second and third embodiments are identical to the rear, side, and top views illustrated in FIGS. 3-5 for the first embodiment. In addition, the bottom views of the second and third embodiments are omitted because those bottom views are plain and unornamented.
